UNITED STATES PATENT OFFICE.

ANDREW EPPLER, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,355,824.

Specification of Letters Patent. Patented Oct. 19, 1920.

Application filed November 27, 1916. Serial No. 133,625.

To all whom it may concern:

Be it known that I, ANDREW EPPLER, a citizen of the United States, residing at Lynn, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates particularly to sewing-machines of the type employed to sew together the upper and the sole of a turn-shoe, or the upper, insole and welt of a welt-shoe, although certain features of the invention may be applicable to sewing-machines of other types.

One object of the invention is to improve the operation of the back-gage, or the combined back-gage and welt-guide, commonly employed in machines of the type in question. This member is commonly retracted from the work during the feed-movement, and is then advanced into, and locked in, engagement with the shoe-upper so as to support the work during the retreating movement of the needle. Owing to the variations in the thickness of the work the advancing movement of the back-gage must occur through varying distances, and accordingly a spring is commonly used for the purpose, while the retracting movement is produced by cam-actuated mechanism.

In certain well-known machines, the retracting-mechanism is provided with a clutch-device operable in a direction to retract the back-gage, and movable always through a fixed distance. This mechanism acts to initiate the retracting movement always at a given point in the cycle of operations of the machine, and to retract the back-gage always to a fixed distance from the work, regardless of the thickness of the work and the resulting initial position of the back-gage. It is also provided with means for tripping the clutch-device at the forward end of its path of movement, so as to leave the back-gage free to advance, under the influence of its spring, beyond the position which it occupied at the commence-

ment of the preceding retracting movement, in case the intervening feed-movement may have brought into operative position a thinner part of the work than that previously engaged.

An object of the present invention is to improve the mechanism just described, particularly with a view to preventing the hammering action of the back-gage against the work which sometimes occurs. As a part of the means to this end it is proposed to provide means by which the clutch-device is tripped, so as to release the back-gage, at the rear end of its path of movement, either in place of, or in addition to, the usual means for tripping the clutch-device at the forward end of its path. In order, however, that the back-gage may be still controlled and retained in retracted position at this time, power-actuated means are provided for the purpose, and these means are arranged to control the advancing movement of the back-gage throughout the later part of the movement, during which the back-gage comes into engagement with the work.

By the arrangement just described it is insured that the back-gage shall never engage the work while under uncontrolled spring-actuated movement, as may occur in a machine of the previous construction described, and thus one cause of possible hammering is eliminated. Another advantage of the present construction pertains particularly to the use of frictional or roller-wedge clutch-devices. When a clutch-device of this type is employed it tends to become bound, while retracting the back-gage against the resistance of the advancing-spring, so that a sensible force is required to loosen the parts, and if this force is exerted against the back-gage at the moment of its impact against the work the tendency to hammering is accentuated. In the present construction the clutch-device is tripped at the rear end of its path of operation, as before stated, and since it does not act to restrain the advancing movement of the back-gage, by reason of the provision of other means for that purpose, the clutch is never bound or set at the moment when the back-gage

encounters the work, and cannot, therefore, add any force to the impact of the back-gage.

In the accompanying drawings Figure 1 is a side-elevation of a sewing-machine embodying the present invention, looking from the right, and Fig. 2 is a side-elevation looking from the left. Figs. 3 and 4 are, respectively, a left-hand side-elevation and a plan-view of portions of the mechanism including particularly the means for actuating the back-gage, these figures being on a larger scale than Figs. 1 and 2. Fig. 5 is a detail-view, in section, of the adjustable connection between certain parts of the back-gage mechanism. Fig. 6 is a detail-view, in left-hand side-elevation, showing particularly the parts of the mechanism for actuating the looper and the thread-fingers. Fig. 7 is a detail-view of the same parts in side-elevation, looking from the right, with certain portions in vertical-section. Fig. 8 is a detail-view, partly in vertical section, of a portion of the means for supporting and heating the looper. Fig. 9 is a front-elevation of parts of the machine, including particularly the mechanism for supporting and guiding the looper and for heating the looper and the channel-guide. Figs. 10 and 11 are fragmentary views, in side elevation and front-elevation respectively, illustrating the operation of certain of the sewing-instrumentalities, including the thread-fingers, these parts being shown exaggerated in size; and Figs. 12 and 13 are similar views showing the parts in a different position.

The invention is illustrated as embodied in a sewing-machine of the type employed in producing the inseam of a welted shoe or a turn-shoe, and the illustrated machine is adapted particularly for sewing turn-shoes, being provided with a back-gage but no welt-guide. In its general construction and mode of operation the machine is similar to that disclosed in United States Letters Patent to Andrew Eppler, No. 1,108,560, issued August 25, 1914, and accordingly the machine will be described only in so far as is necessary for an understanding of the present invention.

The illustrated machine is provided with the usual sewing-instrumentalities, including a curved hooked needle 16, a looper 18, a feed-point 20, a channel-guide 22, a back-gage 24 and a back-rest 26. The mechanism is actuated by a cam-shaft 28 bearing the usual disk-cams.

The mechanism for actuating and controlling the back-gage 24, in which certain features of the present invention are embodied, is shown particularly in Figs. 2, 3, 4 and 5. The back-gage is formed integrally with the forward end of a lever 30, and this lever is supported, at an intermediate point, by

means of a second lever 32, which is provided, at its upper end with an integral stud 34. This stud turns in a bearing in a member 36 of the stationary frame of the machine. The rear end of the lever 30 is supported by means of a roller 38, which is journaled thereon, this roller being free to move forwardly and rearwardly in an inclined guideway 40 which is fixed on the frame of the machine. The levers 30 and 32 are pivotally connected by means of a stud 42, which is fixed in the lever 32 and turns in a bearing in the lever 30. As shown in Fig. 5 this stud is eccentric, so that by turning it into and fixing it in different positions in the lever 32 the lever 30 may be raised or lowered to adjust the back-gage vertically.

It will be observed that the stud 34 of the supporting-lever 32 is so located that the swinging movements of this lever cause its lower end to move in an arc which is downwardly and forwardly inclined, and that the rear end of the back-gage lever 30 is guided in a similar path by the guide-way 40. In consequence of this arrangement the back-gage 24 moves in a slightly curved downwardly and forwardly-inclined path, which corresponds approximately to a portion of the path of movement of the needle 16, so that the back-gage remains in proper operative relation with the needle in all positions in which it may engage the shoe which is being sewed. At the same time the angular position of the back-gage is maintained practically invariable throughout its forward and rearward movements, so that the angle of presentation of the back-gage to the shoe is always the same.

Advancing movements of the back-gage are produced normally by the action of a spring 44. The spring is coiled around a stud 45 on the frame, as shown in Fig. 1, while its upper end bears against a pin 46 projecting from the back-gage lever 30, and thus tends to thrust this lever forwardly.

The back-gage is retracted, and its advancing movement is controlled, by power actuated mechanism. For this purpose a horizontal slide-guide 48 is provided on the main portion 50 of the frame of the machine, and a slide 52 moves in this guide. The slide is connected with the lever 32 by means of a link 54 in the form of a flat straight bar. The rear end of the bar is pivotally connected with the slide by means of an enlarged head 56 on the bar, which fits closely but turns in a corresponding recess in the forward end of the slide. The forward end of the bar is pivoted to the lever 32 by means of a stud 58. This stud is fixed in a vertical slot in the lever, and it may be adjusted to different positions therein so as to vary the amplitude of the

movements imparted to the back-gage by means of the power-mechanism.

Cam-mechanism is employed to provide the power for actuating the back-gage. For 5 this purpose a cam-lever 60 is mounted on a pivot 62 (Fig. 2) on the frame of the machine, and this lever carries, at its upper end, a roller 64 which co-operates with one of the cam-disks on the shaft 28. The cam- 10 mechanism acts upon the back-gage through two means, one of which is positive and invariable in its action, while the other is in the form of a one-direction clutch. This clutch comprises a body 66 which is slotted 15 to embrace and slide upon the bar 54, being retained thereon by a back-plate 68 screwed to the body (Fig. 4). The clutch-body is provided with a recess 70 in which a roller 72 is carried in contact with the bar 54, and 20 this recess is inclined, as shown in Fig. 3, so that when the clutch is moved rearwardly the roller tends to wedge between the bar and the inclined surface of the recess, and thus to grip the bar and cause it to move 25 rearwardly with the clutch. This action is facilitated by a spring 74 seated in the clutch-body and engaging the roller. The roller is retained in the recess 70 by means 30 of a cover-plate 76 which is screwed to the clutch-body.

The clutch is connected with the cam-lever 60 by means of a link 78, so that the cam-lever imparts reciprocating movements of invariable amplitude to the clutch at definite 35 times in the cycle of operations of the machine. Accordingly the clutch, at the beginning of its rearward movement, seizes the bar 54 and thus imparts a rearward movement to the back-gage at a definite point in 40 the cycle of operations of the machine, this point being determined as shortly before the commencement of the operative movement of the feed-mechanism. The clutch also retracts the back-gage through a definite dis- 45 tance, this distance being such as is sufficient in all cases to remove the back-gage from contact with the shoe and hold it clear of the shoe during the feeding and swinging movement thereof.

50 In order to trip the clutch, so as to leave the back-gage free to advance as far as may be necessary in each case to reengage the shoe, a trip-lever 80 is pivoted to the clutch-body and provided with a finger 88, which is ar- 55 ranged to engage the roller 72. A spring 90, which is seated in the clutch-body, engages the lower end of the trip-lever and normally holds the lever in inoperative position with a stop-lug 81, formed on the lever, in engage- 60 ment with the cover-plate 76. A trip-plate 94 is fixed to the frame of the machine in such a position that a rearward projection 92 thereon engages the trip-lever near the extremity of the forward movement of the 65 clutch, so that the trip-lever is swung upon

the clutch-body sufficiently to cause the finger 88 to press the roller 72 rearwardly and release it from wedging-engagement with the bar 54. If at this time the back-gage has not yet encountered the surface of the shoe 70 the spring 44 can continue to move the gage forwardly until it is pressed against the work.

As so far described the back-gage actuating mechanism, except for details of form 75 and construction, is substantially the same in organization and mode of operation as that disclosed in the said Patent No. 1,108,560. A feature of the present invention, however, resides in the provision of means for tripping the clutch at the rear end of its path of movement. For this purpose the trip-lever 80 is provided with an upwardly-extending arm 82 which co-operates with a shoulder 84 formed on a stationary member 86 of the 80 frame of the machine. When this shoulder is encountered the trip-lever is rocked so as to cause the finger 88 again to press back the roller 72 and thus release the bar 54.

It will be apparent that when the clutch-lever is tripped by the means last described it is necessary to control the back-gage by means other than the clutch, in order that it may not be thrust forwardly at once by the spring 44. Accordingly the slide 52 is pro- 90 vided with two lugs 96 and 98, while the stud 100, which pivotally connects the cam-lever 60 and the link 78, is extended in- 95 wardly to co-operate with these lugs thus forming a lost motion connection between 100 the cam lever and the slide. When the clutch is tripped by the action of the shoulder 84 the spring 44 tends to move the back-gage forwardly, but this movement is ar- 105 rested by the engagement of the lug 96 with the stud 100, as shown in Figs. 3 and 4. The back-gage is thus held retracted until the proper time for its advancing movement, and this latter movement is then controlled 110 positively by the cam-mechanism, this con- trol enduring until the back-gage reaches the surface of the shoe, regardless of the ex- 115 tent of the advancing movement. If the back-gage encounters the shoe in a more in- 120 ward position than that from which it was last previously retracted, owing to the fact that the feed-movement has brought a thicker part of the work into operative position, the shoe will be encountered before the completion of the forward movement of the clutch-device, and in this case a free relative 125 movement of the clutch-device will occur after the movement of the bar 54 has been arrested. Owing to the fact, however, that the clutch has been previously tripped and has not in the meantime performed any holding function upon the bar, this relative movement can occur without any substantial tendency of the clutch to add to the forces by which the back-gage is advanced 130

into contact with the work. If, on the other hand, the back-gage does not encounter the work before the clutch attains its foremost position, the clutch is tripped by the action 5 of the trip-plate 94 so that the forward movement of the bar 54 may be continued until the back-gage has engaged the work.

In the normal operation of the machine the last-described feature of operation, 10 namely, the tripping of the clutch by the plate 94 and the continued forward movement of the bar 54 thereafter, will not occur, and, in fact, it is one of the advantages of the present construction that this mode of 15 operation is normally eliminated. It will be apparent that the engagement of the lug 96 with the stud 100, during the advancing movement of the parts, necessarily involves the fact that when the cam-lever has moved 20 to its foremost position the back-gage will have reached the foremost position possible within the limitations of the mechanism, so that in the presence of a shoe the forward movement of the back-gage must necessarily 25 have been interrupted by contact with the shoe, in every case, before the clutch has reached its foremost position. Accordingly, the trip-plate 94 performs no useful function in the normal operation of the machine. 30 It is desirable, however, that the force of the spring 44 be as light as possible, in order to minimize the pressure of the back-gage against the work, and it may therefore occur that, owing to any unusual friction in the 35 mechanism, the spring may fail to advance the back-gage fast enough to maintain the lug 96 in engagement with the stud 100. In such a case the operation of the trip-plate 94 permits the full advance of the back-gage which might otherwise not occur.

The lug 98 performs no function in the normal operation of the mechanism, but it is useful to prevent accident to the mechanism. In case the operator presses the shoe 45 rearwardly against the back-gage, so as to move the latter to a retracted position, the lug 98, by engagement with the stud 100, limits this movement to an amplitude such that upon the succeeding retracting operation of the back-gage mechanisms the parts immediately connected with the back-gage shall not be drawn beyond the extreme rearward position to which they can be safely retracted. During the operation of the ma- 50 chine the back gage slide 54, which is normally moved forwardly by the spring 44 to bring the back gage into engagement with the work, may not advance owing to some unusual friction. If the slide 54 is held 55 against forward movement in this manner the projection 100 will strike against the lug 98 formed on the slide 54 and positively move said slide forward so as to bring the back gage into engagement with the work.

When the back-gage is in operative engagement with the shoe it is locked in position in the usual manner. For this purpose cam-actuated means are employed, which are similar to those disclosed in said Patent No. 1,108,560, these means comprising a reciprocating wedge-member 102 (Fig. 3) which acts to force a roller 104 into engagement with the slide 52 so as to cramp the latter within the slide-guide at the proper time. 75

The operation of the back-gage mechanism as a whole is as follows: Assuming that the back-gage is in operative engagement with a shoe which is being sewed, and that a stitch has been set by the retracting 80 movement of the needle, the back-gage is unlocked by a retracting-movement of the wedge-member 102, and the cam-lever 60 then swings rearwardly for the purpose of retracting the back-gage. At the commencement of this movement the clutch-device is disengaged from the trip-plate 94, so that the clutch acts to seize the bar 54 and draw it rearwardly, this movement beginning at a predetermined point in the cycle of operations, shortly before the feed-movement of the shoe. The action of the clutch continues substantially throughout the rearward movement of the cam-lever, so that the back-gage is retracted through a definite 90 distance regardless of the exact position which it occupied at the beginning of the movement. Finally, the clutch is tripped at the rear extremity of the movement of the clutch, and the cam-lever thus releases 100 the bar. The spring 44 then acts to advance the back-gage, but this advance is arrested by engagement of the lug 96 with the stud 100, so that the back-gage does not advance at this moment into engagement with the shoe. At the proper time, however, the cam-lever advances again, thus permitting the spring 44 to advance the back-gage farther, and this controlled movement of the back-gage continues until the back-gage is 105 pressed against the surface of the shoe. This always occurs, in the normal operation of the mechanism, before the completion of the forward movement of the cam-lever, and the last part of this forward movement is therefore idle, the clutch sliding idly over the bar 54 until it has reached its foremost position again. 110

It will be apparent that in the present construction the only free or uncontrolled 120 forward movement of the back-gage under the influence of the spring 44 is that which occurs when the back-gage is in retracted position and which results in bringing the lug 96 into engagement with the stud 100. 125 Since the back-gage at this time cannot encounter the shoe, there is no possibility of its producing a hammering action against

the shoe, such as may occur when the baggage has a free spring-produced movement at the moment of encountering the work.

The looper-mechanism is shown particularly in Figs. 2, 6, 7, 8 and 9. The looper 18 is fixed in a carrier 106 which comprises two sleeves 108 and 110 connected integrally by a yoke 112. The sleeves are fitted to slide and rock upon a cylindrical bearing-member 114 at the front of the machine. This bearing-member is supported, at the middle, in a bracket 116 which is screwed to the frame of the machine. As shown in Fig. 8 the bearing-member is fixed in the bracket by means of a cotter-pin 118. The yoke 112 spans the bracket 116, so that the looper-carrier may be moved both longitudinally and rotatively upon the bearing-member, and the substantial distance which separates the points of engagement of the sleeves with the bearing-member insures that there shall be a minimum degree of lost motion between the parts and a correspondingly high degree of accuracy in the control of the movements of the looper.

The looper is actuated by cam-mechanism, and its traversing movements are produced by a cam-lever 120 (Fig. 2) which carries, at its lower end, a roller engaging a peripheral groove on one of the cam-disks on the shaft 28. At its upper end the cam-lever is fixed to a forwardly-extending rock-shaft 122. A lever 124 depends from the forward end of the rock-shaft, and the lower end of this lever is slotted (Figs. 7 and 9) and embraces a block 126 which is pivoted on a stud 128 projecting from the yoke 112. Through this arrangement rocking-movements of the cam-lever are transmitted to the looper-carrier so as to slide the latter longitudinally on the bearing-member 114, while, by the use of the block 126 and the slotted end of the lever 124, interference with the rocking-movements of the looper-carrier is avoided. The rocking-movements of the looper-carrier are produced by a slide 134 (Fig. 2) which moves forwardly and rearwardly in a guideway on the frame of the machine. This slide carries, at its rear end, a roller 136 which engages a slot in one of the cam-disks, while the forward end of the slide is provided with a stud 138. This stud slides in a sleeve 140 at the upper end of a stem 142, and the stem is slidingly mounted in an arm 144 projecting upwardly from the yoke 112. The forward and rearward movements of the slide 134 are thus communicated as rocking movements to the looper-carrier, and the engagement of the stud 138 with the sleeve 140 is such as not to interfere with the longitudinal movements of the looper-carrier.

The bearing-member 114 is utilized as means for heating the looper. For this

purpose a U-shaped steam-passage 146 is formed within the bearing-member, this passage being connected, at its ends, with pipes 148 through which steam or other heating-fluid may be introduced and discharged. The heat of the bearing-member is conducted directly through the looper-carrier to the looper.

In machines of the type in question wax from the thread frequently drops and collects upon the channel-guide, so that it is necessary for the operator to remove it. A feature of the present invention resides in the use of means by which the channel-guide is heated, so that any wax which falls upon it is melted and runs away. The channel-guide 22 is fixed to a plate 150 which, in turn, is adjustably fixed to the lever 152 by which the channel-guide is supported and actuated in the same manner as in the machine of said Patent 1,108,560. As a convenient means for heating the channel-guide the plate 150 is provided with a sleeve 154 in which a spring-pressed plunger 156 moves, the head of this plunger being in engagement with the end of the bearing-member 114, and remaining in such engagement notwithstanding the transverse and fore-and-aft movements of the channel-guide. Accordingly heat is conducted directly from the bearing-member 114 through the plunger 156, the plate 150 and the shank of the channel-guide, so that the channel-guide and its shank are kept hot by direct metallic conduction.

The machine illustrated herein is provided with a thread-finger 158 which corresponds, in form and in mode of operation, with the thread-finger disclosed in said Patent 1,108,560. This thread-finger is fixed adjustably, by means of a screw 160, to a short rock-shaft 162 which turns in a bearing in the bracket 116. An arm 164 (Fig. 2) is fixed to the opposite end of the rock-shaft, and this arm is connected by a link 166, to a cam-lever 168. The cam-lever is mounted on a pivot 170 on the frame of the machine, and it carries a roller 172 which engages a groove in one of the cam-disks on the shaft 28.

In addition to the usual or main thread-finger 158, the present machine is provided with a supplementary thread-finger 174. It has been previously proposed to employ such a supplementary thread-finger to coöperate with the main thread-finger in drawing out and holding the thread which is later to be given up to the needle, the function of this supplementary thread-finger being to form a support around which thread can be drawn by the main thread-finger, and to thereby prevent the thread so drawn from pulling the channel-flap upwardly and rearwardly to an undue extent, while so insuring

the drawing-out of a definite length of thread. In the present construction this supplementary thread-finger is arranged to move in a downwardly and rearwardly inclined path and into engagement with the upper surface of the channel-flap, as shown particularly in Fig. 12, so as to perform the function just described and also to press the channel-flap down and leave it in a depressed position after the stitch has been formed. A feature of the present invention resides in the simple and effective means employed for actuating the supplementary thread-finger. For this purpose a slide-guide 176 is formed on the bracket 116, as shown in Fig. 7, and the shank of the thread-finger 174 is arranged to slide in this guide. This shank is also provided with rack-teeth, which mesh with the teeth of a pinion 178 which is fixed on the rock-shaft 162 by which the main thread-finger 158 is actuated. Accordingly, when the main thread-finger is swung inwardly in the performance of its thread-drawing function, the supplementary thread-finger is moved downwardly and rearwardly, so as to assist in drawing out the thread and pressing and holding down the channel-flap.

Figs. 10 to 13 show two successive positions of the two thread-fingers and other sewing-instrumentalities. In Figs. 10 and 11 the looper has thrown the thread between the ends of the thread-fingers, the needle at this time being in its retracted position. In Figs. 12 and 13 the parts are shown in a subsequent position, in which the main thread-finger has moved rearwardly and the supplementary thread-finger has moved downwardly into engagement with the channel-flap 180 of the insole 182. In these latter figures the needle has advanced and the looper has cast a loop of thread into the hook of the needle. Upon the subsequent retraction of the needle the movement of the thread-fingers is reversed, so that the bight of thread held by them is slackened and given up to the needle, thus in the usual manner preventing reeving of the thread through the hook of the needle.

The improved mechanism for actuating the looper and the thread fingers is not covered in the claims of this application, but such devices are described and claimed in an application, Serial No. 210,849, filed January 8, 1918, which application constitutes a division of the present application. The heating devices, herein described, for heating the looper and the channel guide are not claimed in this application, but such devices constitute the subject-matter claimed in application Serial No. 212,042, filed January 16, 1918, said application being a division of this application.

While the several features of the invention

hereinbefore described are adapted for joint use in a sewing-machine of the wax-thread type for sewing inseams, it will be apparent that they are not necessarily always used in conjunction, and that certain features of the invention may be applicable for use in machines of other types. The invention is not, in general, limited to the embodiment thereof hereinbefore described and illustrated in the accompanying drawings, but it may be embodied in other forms within the scope of the following claims.

What is claimed is:—

1. In a sewing-machine having, in combination, a back-gage; feeding-means; and actuating mechanism for the back-gage; said mechanism being constructed and arranged to initiate the retracting movement of the back-gage always at a predetermined point in the cycle of operations of the machine, regardless of the thickness of the work, and to return the back-gage into engagement with the work by a controlled advancing movement.

2. A sewing-machine having, in combination, a back-gage; feeding-means; and actuating mechanism for the back-gage; said mechanism being constructed and arranged to initiate the retracting movement of the back-gage always at a predetermined point in the cycle of operations of the machine, retract the back-gage through a constant predetermined distance; and return the back-gage into engagement with the work by a controlled advancing movement.

3. A sewing-machine having, in combination, a back-gage; feeding-means; a spring tending to advance the back-gage into engagement with the work; power-mechanism coöperating positively with the back-gage to control the latter part of its advancing movement under the influence of the spring; and clutch-mechanism actuated by the power-mechanism and coöperating with the back-gage to initiate its retreating movement always at a predetermined point in the cycle of operations of the machine.

4. A sewing-machine having, in combination, a back-gage; feeding-means; a spring tending to advance the back-gage into engagement with the work; power-mechanism coöperating positively with the back-gage to control its advancing-movement; and power-operated clutch-mechanism coöperating with the back-gage to produce the retreating movement thereof.

5. A sewing-machine having, in combination, a back-gage; feeding-means; and actuating-mechanism, for the back-gage, constructed and arranged to produce first a power-controlled retracting-movement, then a free spring-controlled partial advancing movement, and then a power-controlled final advancing movement of the back-gage.

6. A sewing-machine having, in combination, a back-gage; feeding-means; and actuating-mechanism, for the back-gage, constructed and arranged to produce first a retreating movement of limited definite range, and then an advancing movement of variable range, and to control positively the latter part of the advancing movement of the back-edge. 65
- 5 7. A sewing-machine having, in combination, a back-gage; feeding-means; a spring tending to advance the back-gage; power-mechanism for actuating the back-gage; connections, between the back-gage and the power-mechanism, including abutments engageable in a direction to arrest and control the advancing movement of the back-gage, and a clutch operable to retract the back-gage; and means for tripping the 70 clutch substantially at the end of its rearward movement so as to relinquish the back-gage to the control of said spring and said abutments. 75
- 10 8. A sewing-machine having, in combination, a back-gage; feeding-means; and a power-actuated clutch-device coöperating with the back-gage and constructed and operating to retract the back-gage but to release the same at the rear end of the path 80 of movement of the clutch-device. 85
- 15 9. A sewing-machine having, in combination, a back-gage; feeding-means; and a power-actuated clutch-device coöperating with the back-gage and constructed and operating to retract the back-gage but to release the same at each end of the path of movement of the clutch-device. 90
- 20 10. A sewing-machine having, in combination, a back-gage; feeding-means; a spring tending to advance the back-gage; a power-actuated clutch-device constructed and arranged to retract the back-gage and to release the same at the forward end of the path of operation of the clutch-device; and 95 power-operated means for controlling the advance of the back-gage when so released by the clutch-device. 100
- 25 11. A sewing-machine having, in combination, a back-gage; feeding-means; and a power-operated clutch-device and positively-acting power-actuated means both operable to retract the back-gage. 105
- 30 12. A sewing-machine having, in combination, a back-gage; feeding-means; yielding means for advancing the back-gage; and a power-operated clutch-device and positively-acting power-actuated means both operable to control the advancing movement of the back-gage. 110
- 35 13. A sewing-machine having, in combination, a back-gage; feeding-means; a power-operated member; lost-motion connections, between said member and the back-gage, for controlling the movements of the latter in 115
- 40 both directions; and a clutch-device, connected with and actuated by said power-operated member, for retracting the back-gage. 120
- 45 14. A sewing-machine having, in combination, a back-gage; a rearwardly-extending lever carrying the back-gage; a device for guiding the rear end of said lever; a second lever mounted on a stationary pivot, at its upper end, and pivoted, at its lower end, to an intermediate point on the first-mentioned lever; and actuating-mechanism, connected with the second lever, for swinging the latter to cause advancing and retreating movements of the back-gage. 125
- 50 15. A sewing-machine having, in combination, a back-gage; a rearwardly-extending lever carrying the back-gage; a device for guiding the rear end of said lever; a second lever mounted on a stationary pivot, at its upper end, and pivoted, at its lower end, to an intermediate point on the first-mentioned lever; and actuating-mechanism, connected with the second lever, for swinging the latter to cause advancing and retreating movements of the back-gage, the connection between the two levers being adjustable to vary the height of the back-gage. 130
- 55 16. A sewing-machine having, in combination, a back-gage; a rearwardly-extending lever carrying the back-gage; a device for guiding the rear end of said lever; a second lever mounted on a stationary pivot, at its upper end, and pivoted, at its lower end, to an intermediate point on the first-mentioned lever; and actuating-mechanism, connected with the second lever, for swinging the latter to cause advancing and retreating movements of the back-gage, the connection between the actuating-mechanism and said second lever being adjustable longitudinally of the lever to vary the amplitude of the movements imparted to the back-gage. 135
- 60 17. A sewing-machine having, in combination, a back-gage; power-operated actuating-mechanism, for the back-gage including a clutch device, having a constant range of movement; and connections, between said mechanism and the back-gage, adjustable to vary the amplitude of the movements transmitted from said mechanism to the back-gage. 140
- 65 18. A sewing-machine having, in combination, a back-gage; a lever connected therewith; power-operated actuating-mechanism including a clutch device; a link connected to said mechanism; and connections between said link and said lever, adjustable along the lever to vary the length of the lever-arm through which the link acts upon the lever. 145
- 70 19. A sewing-machine having, in combination, a back-gage; a slide; power-mecha-

nism for moving the slide; connections, between the back-gage and the slide, including a lever, and a link connecting the lever and the slide; and a power-operated clutch-device, for retracting the back-gage, operable on said link.

20. A sewing-machine having, in combination, a back-gage; and actuating mecha-

nism, for the back-gage, comprising a reciprocating member, a one-direction clutch, 10 device coöperating with said member, power-mechanism for reciprocating the clutch-device, and stationary trip-devices for tripping the clutch-device near both ends of its path of movement.

ANDREW EPPLER.
